UNITED STATES PATENT OFFICE.

EDWARD L. AIKEN, OF SPRINGFIELD, MASSACHUSETTS.

SCREW-DRIVER AND OTHER TOOL.

1,158,765.

Specification of Letters Patent.

Patented Nov. 2, 1915.

Application filed January 18, 1915. Serial No. 2,966.

To all whom it may concern:

Be it known that I, EDWARD L. AIKEN, a citizen of the United States of America, and resident of Springfield, in the county of 5 Hampden and State of Massachusetts, have invented certain new and useful Improvements in Screw-Drivers and other Tools, of which the following is a full, clear, and exact description.

10 This invention relates to improvements in a tool, such as a screw driver, wrench, etc., of the kind having the capability of a ratchet action, that is one in which the tool-shank or spindle will be forcibly rotatively moved when the member through which the power is applied is turned in one direction, such shank remaining passive and unaffected by the power member when the latter is 15 reversely turned.

20 The object of the present invention is to provide a tool having the "ratchet action" but in which, however, there is, instead of pawls and ratchet wheels, and parts co-operative therewith novel devices of dissimilar and simplified character which are 25 entirely efficient, preferable to ratchet devices, and generally satisfactory and desirable.

A further object of the invention is to 30 provide constructions and arrangements in the tool whereby the shank or work member thereof may, as elected, be turned forwardly or backwardly under the forcible impulses, rotatively, of the handle or power member,—the relatively reversed movements of 35 the power member being ineffective for the turning of the tool shank.

The invention is described in conjunction 40 with the accompanying drawings and is set forth in the claims.

In the drawings:—Figure 1 is a central longitudinal sectional view of a screw driver embodying this invention. Fig. 2 is a central longitudinal sectional view through the 45 portion of the device in which the principal portions of the invention are embodied, on a larger scale for increased clearness of illustration. Figs. 3 and 4 are cross sectional views on lines 3—3 and 4—4, Fig. 1, respectively, as seen in the directions indicated by the arrows shown in conjunction with the section lines. Fig. 5 is a side view of the locking or binding members removed from their place of action in the tool. Fig. 6 is 50 an end view showing constructions or for-

mations provided at the lower end of the handle or power member.

Similar characters of reference indicate corresponding parts in all of the views.

I will proceed to describe the tool, here 60 exemplified as a screw driver exactly and specifically as the same has been constructed by me, it being understood that changes and departures from these constructions may be 65 made within the scope of the invention and the purview of the claims without departure therefrom.

In the drawings.—A represents the shank, spindle, or work member of the tool having at an intermediate portion thereof a fixed cylindrical or cup-shaped casing B, the same having the upwardly opening circular chamber *a* therein, and a circular cavity *b* of reduced diameter.

C and D represent approximately semi-spherical friction shoes normally loosely fitted in the circular cavity or chamber *b* in the casing B, one being somewhat wider than the other as shown in Figs. 3, 4 and 5; and these friction shoes or binding members are adapted to have separating movements one relatively to the other for engagement against the wall in the casing which surrounds them. *b b* represent fulcrum members between said shoes at points 85 opposite the axis of the tool. In the present instance the adjacent inner edges of the shoes have vertical grooves or arc shaped channels parallel with the axis of the device, within, and retained by which, are small cylindrical blocks constituting the fulcrum members *b*. The wider shoe C has a rabbet in its top opening to its narrow edge whereby a straight backing-up shoulder *d* is produced.

F F represent a pair of lever members, oppositely located and set within the rabbet of the shoe C, and by pivots *e* connected and adapted for swinging movement relatively thereto. Each lever bar F is backed up at its one edge by the aforementioned shoulder *d* whereby the said bars are in alignment diametrically of the tool but the said lever bars may either of them,—but one at a time only,—be swung away from 100 the backing up shoulder *d* to edgewise engage and exert a crowding action against the other shoe D.

G represents the handle loosely encircling the portion of the tool shank or spindle A 110

above the cylindrical casing B; the same having a retaining nut *c* on its upper end, between which and the internal shoulder *f* at the bottom of the counterbore in the handle a spring *g* is provided under compression; the handle is, therefore, capable of an endwise movement, as well as a rotative movement relatively to the spindle; and the spring is effective for normally forcing the handle down toward the casing, and holding it against accidental displacement upwardly.

The handle has at its lower end an annular flange *J* concentric with the axis of the tool formed with recesses *h* and *i* diametrically opposite one another. The recess *h* is of a width corresponding to that of the lever bars *F* so that the flanged lower end extension of the handle may have a straddling engagement over either one or the other of the end portions of the lever bars which outwardly project beyond the edges of the shoes. The other oppositely located recess *i* in the annular flange of the handle is considerably wider than the recess *h* so that while the handle, by reason of the straddling engagement which its recessed flange has with one of the lever bars is effective, under the rotative movement of the handle in one direction, to swing such lever bar, the flange by reason of the opposite recess being so wide will not affect, or be obstructed by, the opposite lever bar in the operation or use of the tool.

Assuming the handle is adjusted with relation to the clutching devices as represented in Fig. 3, that is with the narrow recessed portion of the flange in engagement with the lever bar which is shown uppermost, the turning of the handle in the direction of the arrow will swing the lever bar in the corresponding direction with the result of edgewise engaging the shoe *D* and swinging it from the relatively lower one of the fulcrums *b* to its bind with the wall of the casing, and compel the shank of the screw driver to be turned in conjunction with the handle. There will be, by reason of the crowding action as between the two shoes in opposite directions, a binding action by the shoe *C* as well also as by the one *D*.

The rotative movement of the handle with its flange in a direction the reverse of the arrow shown in Fig. 3 relieves the frictional binding action of the device and the handle is free to be reversely turned for a half a rotation, or to any extent of rotative movement preparatory to the next working impulse by the again turning of the handle in the direction of the aforementioned arrow.

The parts conditioned or adjusted as represented in Fig. 3 are such as to afford a forward or right hand driving action of the screw driver *A* or other work member; but by diametrically reversing the relations of the parts from those represented in Fig. 3,

that is having the part of the annular flange *J* which is provided with a narrower recess *h* in engagement with the relatively lower one *F* of the lever bars, the screw driver or work member will then be in clutch for the reverse or leftward turning of the handle or power member as desirable for an unscrewing action.

The shifting or reversal of the handle provided with the recessed annular flange *j* to a position diametrically opposite from one previously assumed is most easily and readily accomplished by the endwise drawing of the handle upwardly sufficiently for the recessed flange to be edgewise clear of the tops of the lever bars; and then upon half a rotation, and on the release of the outward endwise force on the handle the spring is effective for the reengagement of the handle with the particular one desired of the lever bars.

The nut *c* is made with a flange *c²* at its outer end to form a limiting abutment for the shoulder *c³* at the base of the circular rabbet in the upper bored end of the handle.

The flange or wall *m* of the cup or casing *B* is of a size, diametrically, to closely fit about and inclose the recess-provided flange *j* which is appurtenant to the handle, thereby lending an attractively simple and slightly aspect to the tool, and functionally serviceable to exclude dust, dirt or extraneous matter from entrance into the working parts of the device.

While the tool has been shown and described as one having the capability of reversal, whereby the work member may, as elected, be forwardly or reversely driven, for the maximum utility of the implement, the invention is not understood as necessarily, in all respects, limited to its duplicated and reversible character; for the invention is susceptible of being embodied in a manifest way in a tool having the capability of only a "one way" rotative driving action.

As obvious the work member constituted by the shank or spindle *A* instead of being formed as a screw driver may be made as a tool of different character and the design of the power members or handle may be considerably modified from that shown, without the exercise of further invention.

I claim:

1. In a tool of the character described, in combination, a tool shank having a fixed cylindrical casing, a pair of friction shoes in said casing, one of which is adapted to have a separating movement relatively to the other for a binding engagement against the wall of said casing, a fulcrum member between said shoes whereby the one may have its separating movement from the other pivotally from said fulcrum, a lever bar on the one shoe, edgewise engaged against a

portion of such shoe and prevented from being swung in one direction and edgewise engaging and crowding the other shoe, and a handle member loosely connected with the 5 tool shank, above the casing, for a rotative movement relatively thereto, and having an engagement with said lever bar.

2. In a tool of the character described, in combination, a tool shank having a fixed 10 cylindrical casing, a pair of friction shoes in said casing, one of which is adapted to have a separating movement relatively to the other for a binding engagement against the wall of said casing, a fulcrum member 15 between said shoes whereby the one may have its separating movement from the other pivotally from said fulcrum, a lever bar on the one shoe, having an engagement thereagainst whereby it is prevented from being 20 swung in one direction but capable of swinging in the opposite direction and edgewise engaging the other shoe, and a handle member loosely connected with the tool shank above the casing, for a rotative movement 25 relatively thereto, and having a portion of annular form provided with a recess therein adapted to fit and engage the said lever bar.

3. In a tool of the character described, in combination, a tool shank having a fixed 30 cylindrical casing, a pair of friction shoes in said casing, one of which is adapted to have a separating movement relatively to the other for a binding engagement with the wall of said casing, oppositely located lever 35 bars pivoted on the one shoe, edgewise engaged against such shoe and prevented from being swung in one direction but capable of swinging in the opposite direction and edgewise engaging the other shoe, and a 40 handle member loosely connected with the tool shank above the casing, for a rotative movement relatively thereto, and having an annular flange formed with a recess at one 45 of its sides to fit and engage one of the lever members and having at its opposite side a recess wider than the lever bar, such handle member being diametrically reversible on the tool shank whereby the narrow flange 50 may have engagement with either of the lever bars.

4. In a tool of the character described, in combination, a tool shank having a fixed cylindrical casing, a pair of friction shoes in

said casing, one of which is adapted to have a separating movement relatively to the 55 other for a binding engagement against the wall of said casing, located at separated points, fulcrum members between said shoes whereby the one shoe may have its separating movement from the other pivotally from 60 either fulcrum, lever bars pivoted on the one shoe, and prevented from being swung in one direction relatively to such shoe, but free to swing in the opposite direction for a crowding action against the other shoe, and 65 a handle member loosely connected with the tool shank, above the casing, for a rotative and also a sidewise movement relatively thereto, and having an annular flange provided with opposite recesses one of which is 70 of the width of, and to fit either of, said shoes, and the other of which recesses is wider than said shoes.

5. In a tool of the character described, in combination, a tool shank having a fixed 75 cylindrical casing, a pair of friction shoes of approximately hemi-cylindrical form in said casing, one of which is adapted to have a separating movement relatively to the other for a binding engagement with the 80 wall of said casing, and one of said shoes having a rabbet in its top opening to its inner edge, fulcrum members between said shoes at points opposite the axis of the tool, lever bars oppositely located, set within the 85 rabbet of the shoe and pivoted thereto, the wall of the rabbet being capable of swinging toward and edgewise engaging the other shoe, a handle member loosely connected with the tool shank above the casing, for a 90 rotative movement relatively thereto, and having an annular flange formed with a recess at one of its sides to fit and engage one of the lever members and having at its opposite side a recess wider than the lever bar, 95 such handle member being diametrically reversible on the tool shank whereby the narrow flange recess may have engagement with either of the lever bars.

Signed by me at Springfield, Mass., in 100 presence of two subscribing witnesses.

EDWARD L. AIKEN.
